DISPLAY DEVICE FOR ELECTRIC DRY CELLS OR THE LIKE

Daniel W. Leo, 322 S. Merrick Ave.,
Merrick, N.Y. 11566

Filed Dec. 8, 1972, Ser. No. 313,548

Term of patent 14 years

Int. Cl. D6—04

U.S. Cl. D6—148

FIG. 2

FIG. 1

FIG. 1 is a front perspective view of a display device for electric dry cells or the like, showing my new design; and

FIG. 2 is a rear perspective view with the lid portion removed.

I claim:

The ornamental design for a display device for electric dry cells or the like, substantially as shown and described.
